CLAIM

The ornamental design for a hood for vehicle, as shown and described.

DESCRIPTION

FIG. 1 is a front perspective view of a hood for vehicle showing our new design;

FIG. 2 is a top view thereof;

FIG. 3 is a front view thereof;

FIG. 4 is a rear view thereof;

FIG. 5 is a bottom view thereof; and,

FIG. 6 is a left side view thereof, the right side view being a mirror image of the left side view.

It will be understood that the broken lines shown in the drawings illustrate portions of the hood for vehicle that form no part of claimed design.

1 Claim, 5 Drawing Sheets
